INVENTOR
James E. Middleton
By
W. W. Williamson, Atty.

UNITED STATES PATENT OFFICE.

JAMES E. MIDDLETON, OF PHILADELPHIA, PENNSYLVANIA.

GAS-HEATED HAIRDRESSING COMB.

Application filed April 17, 1922. Serial No. 554,063.

To all whom it may concern:

Be it known that I, JAMES E. MIDDLETON, a citizen of the United States, residing at Philadelphia, in the county of Philadelphia and State of Pennsylvania, have invented new and useful Improvements in a Gas-Heated Hairdressing Comb, of which the following is a specification.

My invention relates to new and useful improvements in a gas heated hair dressing comb, and has for its object to provide an exceedingly simple and effective device of this character whereby a steady heat may be applied to the comb through the medium of a gas or gasoline flame so that the operations of hair dressing may be continuous avoiding the necessity of delays and saving the time and annoyance attendant thereof.

Another object of the invention is to so construct the comb and the burner thereof as to bring about perfect combustion within the heating chamber to facilitate the transmission of heat to the comb teeth.

Another object of the invention is to provide a unique construction of heating element combined with the handle.

Still another object of the invention is to so construct the parts that they will be interchangeable permitting the use of combs of different shapes or the use of a handle without a burner thereby permitting the comb to be heated within a stove or above a flame should the occasion for such mode of heating arise.

A further object of the invention is to provide a comb of this character having arcuate teeth and a circular back so that as the teeth are moved through the hair the strands will first be lifted from the scalp and then ironed out in a satisfactory manner, such operation being carried out by the operator with a mere twist of the wrist.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying

drawing forming a part of this application, in which:—

Fig. 1, is a side elevation of a comb made in accordance with my invention.

Fig. 2, is a longitudinal sectional view thereof.

Fig. 3, is an end view of the comb head.

Fig. 4, is a side elevation of a slightly different formation, a portion of the comb proper being broken away and shown in section to illustrate the details of construction.

Fig. 5, is an end view thereof.

In carrying out my invention as embodied in Figs. 1, 2 and 3, 2 represents the comb which may be made of any suitable material, preferably metal of high heat conductivity, such as copper or aluminum, which consists of the arcuate teeth 3 and the circular back 4, said back being hollow so as to form a combustion chamber 5. From one end of the circular back projects a neck 6 formed either as a part of the comb back or secured thereto in any suitable manner as will be obvious. At the outer end of the neck 6 is formed an enlargement 7 to produce a bore of smaller diameter than the bore through the neck and this enlargement is internally threaded for the reception of the threaded inner end of the tubular shank 8 the inner end of the latter when properly adjusted projecting into the neck 6 beyond the ventilating or exhaust apertures 9 formed in the neck 6 adjacent its outer end. The tubular shank has air inlet openings 10 adjacent its inner end while the outer end is threaded as at 11 for the reception of the terminal 12, said terminal being properly shaped to receive a hose or other suitable fuel conductor.

The terminal 12 carries a relatively small burner tube 13, its inner end having very fine outlet openings for the gas or similar fuel and the inner end of said tube terminates adjacent the air inlet openings 10. A handle 14 of any suitable shape or construction or desirable material, such as wood, is mounted upon the tubular shank between the terminal 12 and the air inlet openings 10.

In practice I have found that the burner and combustion chamber made as here shown

and described is highly efficient in heating the comb and as the flame projected from the burner projects in an approximately straight line to the combustion chamber said flame is not affected by the different positions in which the comb is held during the hair dressing operations.

Further I have found that the particular shape of the teeth in back of this comb permit it to be easily operated by simply twisting the wrist which movement causes the teeth to separate the hairs and bring portions of each to the surface for contact with the ironing surface of the circular comb back thereby bringing about exceedingly good results in a relatively short time.

In Figs. 4 and 5, I have shown a slightly different formation of the device embodied in my invention wherein the comb 15 consisting of the teeth 16 and the back 17 has a casing 18 secured to the back of this comb either by riveting, welding or otherwise and this casing is in the general shape of a triangle, as plainly shown in Fig. 5, with the sides diverging outward from the back of the comb so as to gradually increase the width of the combustion chamber formed by said casing. In the side, top and back walls of the casing are formed a plurality of ventilating or outlet holes 19 which permit the escape of the products of combustion. In one of the end walls of the casing is formed a threaded opening for the reception of the threaded inner end of the shank 8 forming a part of the comb and handle identical in construction with that hereinbefore described and plainly shown in Fig. 2.

The last described form of comb is particularly adapted for use with long hair where the comb is held approximately in only one position and many times drawn through the free ends and as the handle used in both cases is identical the parts may be readily interchanged to meet the prevailing conditions.

It has been found that in some cases the

hair dresser prefers to heat the comb in a stove or over a flame and in such a case the handle may be removed and one without a burner substituted so that the burner will not be damaged during such heating.

Of course I do not wish to be limited to the exact details of construction as herein shown as these may be varied within the limits of the appended claims without departing from the spirit of my invention.

Having thus fully described my invention, what I claim as new and useful is:—

1. The herein described combination of a comb having arcuate teeth and a circular back, said back being hollow to form a combustion chamber, a neck projecting from one end of said back and having outlet openings adjacent its outer end, and a combined handle and burner detachably connected with said neck.

2. The herein described combination of a comb having arcuate teeth and a circular back, said back being hollow to form a combustion chamber, a neck projecting from one end of said back and having outlet openings and an internal thread adjacent its outer end, a tubular shank having both ends externally threaded one of which is screwed into the neck with the extreme inner end projecting beyond the outlet openings, said shank having air inlet openings adjacent the inner threaded end, a terminal having threaded connection with the outer end of the shank, a burner tube carried by said terminal and projecting into the shank with its inner end terminating short of the air inlet openings, and a handle on said shank.

3. As an article of manufacture, a comb having a circular hollow back and arcuate teeth projecting therefrom with the outer surface of said teeth blending into the surface of the back.

In testimony whereof, I have hereunto affixed my signature.

JAMES E. MIDDLETON.
